(57) **CLAIM**

The ornamental design for a “companion escutcheons”, as
shown and described.

DESCRIPTION

FIG. 1 is a right front top perspective view of the “companion escutcheons” design according to our invention;
FIG. 2 is a front elevational view of the “companion escutcheons” shown in FIG. 1;

FIG. 3 is a top elevational view of the “companion escutcheons” shown in FIG. 1;

FIG. 4 is a bottom elevational view of the “companion escutcheons” shown in FIG. 1;

FIG. 5 is a left side elevational view of the “companion escutcheons” shown in FIG. 1;

FIG. 6 is a right side elevational view of the “companion escutcheons” shown in FIG. 1;

FIG. 7 is a right front top perspective view of a second
embodiment of the “companion escutcheons” design
according to our invention;

FIG. 8 is a front elevational view of the second embodiment
of the “companion escutcheons” shown in FIG. 7;

FIG. 9 is a top elevational view of the second embodiment
of the “companion escutcheons” shown in FIG. 7;

FIG. 10 is a bottom elevational view of the second embodiment
of the “companion escutcheons” shown in FIG. 7;

FIG. 11 is a left side elevational view of the second embodiment
of the “companion escutcheons” shown in FIG. 7; and,

FIG. 12 is a right side elevational view of the second
embodiment of the “companion escutcheons” shown in FIG.
7.

The rear view of the “companion escutcheons” is not
included and forms no part of the design.

Portions of the companion escutcheons are shown in phan-
tom lines and form no part of the design.
